UNITED STATES PATENT OFFICE.

MILTON N. LATTA, OF VALENTINE, NEBRASKA.

REVERSIBLE HYDRAULIC WELL-DIGGING MACHINE.

1,274,903.

Specification of Letters Patent.

Patented Aug. 6, 1918.

Application filed April 5, 1918. Serial No. 228,874.

To all whom it may concern:

Be it known that I, MILTON N. LATTA, a citizen of the United States, and resident of Valentine, in the county of Cherry and State of Nebraska, have invented certain new and useful Improvements in Reversible Hydraulic Well-Digging Machines, of which the following is a specification.

My invention relates to improvements in well digging apparatus and is more particularly an improvement in the means for creating a continuous suction in the drill tube.

An object of my invention is to provide a well digging apparatus including an automatically operating plunger arranged to act when the cranks pass the dead centers at which time there is a tendency toward a break in the continuity of the fluid stream, to create an auxiliary suction in the pipe and prevent the break in the fluid stream.

Another object of the invention is to provide a well digging apparatus as described, arranged to be reversible with respect to the introduction of the fluid into the drill tube or the bore of the well.

Another object of the invention is to provide in a well drilling apparatus, a pump cylinder having a plunger controlling an oscillating column of water, the plunger having means for permitting the escape of air bubbles to the atmosphere and permitting sufficient water to escape through the plunger and form a seal; the plunger rod operating through the open end of the cylinder and by this arrangement avoiding the necessity of a stuffing box.

Other objects and advantages will appear in the following specification, reference being had to the accompanying drawings in which—

Figure 1 is a perspective view of the invention.

Fig. 2 is a section on the line 2—2 of Fig. 1.

Fig. 3 is a vertical section of one of the pump cylinders illustrating how the water and gravel column oscillates therein.

Fig. 4 is a detail section of the automatic pump cylinder, and

Fig. 5 is a cross section on the line 5—5 of Fig. 4.

In carrying out my invention, I provide a pair of pump cylinders 1 and 2 which are open at the top, and at the bottom are screwed into T's 3 and 4 which provide supports therefor. By way of explanation

and in order that the relative sizes of the various cylinders illustrated in Fig. 1 may be known, it may be stated that the pump cylinders 1 and 2 are approximately four feet high and from eight to ten inches in diameter.

Located at the front of the pump cylinders 1 and 2 or in any other suitable location with respect thereto as may be determined in actual practice, is the automatic pump cylinder 5 which is equal in height to the pump cylinders 1 and 2 but is from four to six inches in diameter. The automatic pump cylinder 5 is supported in a T 6 at the bottom.

Arranged horizontally with respect to the three cylinders just described is an arrangement of connecting pipes which is best shown in Fig. 1. The T's 3 and 4 have nipples 7 at the opposite ends, which connect with inlet and exhaust flap valves 8 and 9. Water and gravel passes through these valves by the force of the suction created by the reciprocating plungers in the pump cylinders 1 and 2. For this purpose the valves 8 and 9 are made ample in their proportions somewhat as shown in Fig. 3, so that there may be no possibility of the parts clogging by an accumulation of gravel or by the passage of an unusually large piece.

Connected to each pair of the flap valves 8 and 9 is a companion pair of elbows 10 and 11 which are directed inwardly and are joined with pipe sections 12 and 13. The pipe sections 12 and 13 have T's 14 and 15 interposed therein. The T 14 lies in a horizontal plane and has a nipple 16 connected thereto, which joins with the T 6 at the bottom of the automatic pump cylinder. The T 15 stands vertically and has the lower end of the exhaust pipe 17 connected thereto.

The exhaust pipe 17 reaches to a plane approximately equal to the tops of the various cylinders, and there has an elbow to which another section 18 of the exhaust pipe is connected. The section 18 extends downwardly and has a laterally extending pipe 19 which reaches into proximity with a water hole H. The reciprocating plungers in the pump cylinders 1 and 2 draw the water out of the well W through the drill tube D and discharge it together with the loosened gravel into the hole H.

At this point it may be mentioned that an important feature is represented by the arrangement just described. The accessi-

bility of the exhaust pipe 19 is a matter of great advantage to the well driller since if he should desire to know the nature of the strata through which he is boring he may 5 simply place a bucket under the discharge end of the pipe and having obtained a bucketful may pour off the water and examine the clay, gravel, or other substance that it may contain.

10 Connected with the T 6 by means of another nipple is an elbow 20 to which a suction pipe 21 is joined. A coupling 22 connects the pipe 21 with the flexible suction hose 23. The suction hose 23 reaches up 15 and connects to the end of a pipe section 24 which in turn is connected to the upper end of the drill tube D by means of a swivel coupling 25. The pipe 24 is supported by a chain 26 which is pendent from a suitable support.

The function of the chain 26 is to provide a movable support for the pipe 24. In the operation of drilling the well the tube D is frequently turned and there is always a 25 great amount of relative movement between the pipe 24 and the drill tube. This necessitates a support for the pipe 24 which is free to give in any lateral direction. In the present instance the coupling 22 is joined 30 to the suction pipe 21 and the water and gravel is drawn through the drill tube D. The cuttings thus move with the swift fluid current. Should it be desired to reverse the connections so that the water be forced 35 into the drill tube and made to boil over the sides of the well bore, the coupling 22 is connected to the end of the discharge pipe 19 as indicated in dotted lines, and the suction pipe 21 is turned into the water in the 40 hole H.

Before proceeding with the description of the more important feature of the automatic pump cylinder and its automatically operating plunger 27, attention is first directed to the operating mechanism of the 45 pump cylinders 1 and 2. The plungers 28 in the respective pump cylinders operate near the normally open ends of the cylinders as illustrated in one instance in Fig. 3. 50 These plungers simply reciprocate within an area of about twenty inches in length and cause the fluid and gravel column to oscillate in the respective pump cylinders from which it is finally discharged through 55 the pipe 19 with the natural and co-operating action of the intake and exhaust flap valves. Each plunger 28 has an extremely small opening 29 in the bottom which is normally closed by a ball valve 30.

60 The function of the hole 29 is to permit any accumulated air beneath the plunger to escape to the atmosphere and the hole is purposely made so small that but a minimum quantity of water will pass through 65 on the down stroke of the plunger. It is

desirable that a certain amount of water accumulate on top of the plunger as illustrated in order to provide a fluid seal. For the purpose of preventing an excessive accumulation of water on top of the plunger, 70 a drain pipe 31 is tapped into one side of the cylinder and this pipe leads directly to the hole H. Were the water permitted to flow over the edge of the pump cylinder, the annoying result of the blowing of the 75 water by the wind would follow.

Supported on a frame 32 is a walking beam 33 to the ends of which the plunger rods 34 are connected. The lower ends of the plunger rods are pivoted to the respective 80 plungers 28, and the rods move freely through the open ends of the cylinders. This arrangement avoids the necessity of the usual stuffing boxes which experience has demonstrated to be very inefficient in this 85 particular connection, for the reason that there is always a great amount of binding at one edge causing excessive wear and an ultimately leaking joint. The fact that in the present invention the water column in 90 the pump cylinders does not approach the upper end but simply follows the reciprocating plungers, makes it possible to employ the operating connections just described and to eliminate the troublesome stuffing box.

95 Journaled in the frame 32 is a shaft 35 which has crank disks 36 at the ends. Crank rods 37 join the disks with the walking beam, and as the disks rotate the walking beam and pump plungers are correspondingly reciprocated. The shaft 35 may be driven by any suitable means, a sprocket 38 being shown on the shaft, to which a chain from another sprocket on an engine shaft 100 may be applied. The suction in the pipe 105 system is the greatest when the wrist pins of the crank rods pass between the dead centers. But when the wrist pins pass over the dead centers, there is a tendency toward a lagging of the force of the suction which 110 the automatically operating plunger 27 corrects.

115 Reference is now directed to Figs. 1 and 4. The pump cylinder 5 is flared at the top to form a funnel 39 and the pipe has a few heavy threads on the inside at the base of the funnel. A perforated ring 40 is screwed 120 into the threaded part and the ring has a square hole 41 in which the square plunger rod 42 operates. The rod 42 has a handle 43 at the top by means of which and through the medium of the square rod, the ring 40 may be unscrewed so that the automatic plunger 27 can be taken out to pour water 125 into the funnel and prime the various cylinders on first starting up.

130 Disposed between a collar 44 on the rod and the ring 40 is a coil spring 45 which is of such a tension that it compresses by a suction of fourteen pounds in the cylinder

5. This suction is created when the wrist pins pass upwardly between the dead centers at which time the greatest suction occurs as stated above. The plunger 27 is accordingly 5 drawn downward against the tension of the spring 45, and when the wrist pins pass over the dead centers, at which time the force of the suction is at a minimum, the spring 45 again expands drawing the plunger 27 up- 10 wardly, acting on the water column in the cylinder 5, continuing the suction in the pipe system and preventing the break that would otherwise occur. By the means just described, a continuous stream of water 15 flows without interruption, and the addition of the automatically operating plunger 27 is one of the most important features in the present invention. Incidentally, the automatic plunger 27 is constructed on the 20 same order as the pump plungers 28, in that it is provided with a minute opening controlled by a ball valve.

This arrangement provides a water seal on top of the plunger and any excessive 25 amount of water flows out of a drain pipe at one side. The ring 40 is the guide for the plunger rod 42 and also the support for the spring 45. The perforations in the ring permit the free passage of air during the 30 movement of the plunger 27.

The operation of the device is as follows:—The pump plungers 28 are made to reciprocate within a short space near the 35 tops of the cylinders 1 and 2 by means of the walking beam 33 and the plunger rods 34. The reciprocating plungers draw the water out of the well through the drill tube D, and control the oscillating water column in each of the pump cylinders. The cut- 40 ings from the bottom of the well are carried with the fluid stream which, being confined to the drill tube, is very swift. These cut- 45 ings are carried into the horizontally dis- posed pipe system at the bottom of the pump cylinders and a short column of the cuttings enters the pump cylinders to approxi- 50 mately the level shown in Fig. 3. On the downward stroke of the plunger the major portion of the water and gravel is forced out.

It occurs sometimes that the cutting tools become clogged and it then becomes desirable to reverse the fluid stream to clean the cutting tools. The reversal of the parts is 55 shown in dotted lines in Fig. 1. When the pump plungers operate, water is drawn out of the hole H and forced into the drill tube D from the top. This makes the water boil up out of the bore of the well and flow back 60 into the hole H.

The action of the automatic plunger 27 is thought to be fully understood, it being sufficient to say that the automatic plunger acts at the time when the wrist pins pass over 65 the dead centers, and creates an auxiliary

suction in the pipe system to keep the fluid stream in continuous motion.

While the construction and arrangement of the device as herein illustrated and described is that of a generally preferred 70 form, obviously modifications and changes may be made without departing from the spirit of the invention or the scope of the claims.

I claim:—

1. In a well digging apparatus, the combination with a drill tube, of a pump cylinder having a plunger, arranged to create a suction in the drill tube, operating means for the plunger including a crank, and means 80 co-acting with the pump cylinder for continuing the suction in the drill tube when the crank passes the dead centers. 75

2. In a well digging apparatus, the combination with a drill tube, of a pump cylinder, pipe connections between the cylinder and tube for drawing water and gravel through the drill tube, a plunger operating in the pump cylinder, crank and connecting devices for reciprocating the plunger to create the suction in the pipe connections and drill tube, and means located in the pipe connection rendered ready when the crank passes upwardly between dead centers and becoming active when the crank passes over 95 the dead centers, to create an auxiliary suction for the continuous flow of the water. 90

3. In a well digging apparatus, the combination with a drill tube, of a pump cylinder, pipe connections between the cylinder 100 and the top of the drill tube, a plunger reciprocating in the upper end of the pump cylinder, a crank having operating connections with the plunger, a cylinder joined in the pipe connections, and means including a 105 plunger in said cylinder arranged to move downwardly when the crank passes upwardly between the dead centers and automatically move upward when the crank reaches the dead centers. 110

4. In a well digging apparatus, the combination with a drill tube, of a pump cylinder in connection with the drill tube, a plunger operating in the pump cylinder to create a suction through the drill tube, a cylinder in the pump and tube connection, a plunger in said cylinder movable downwardly in the cylinder under the influence of the suction, and means including a spring for returning said plunger to create an auxiliary suction and keep the fluid flow in the drill tube and connection continuous. 120

5. In a well digging apparatus, the combination with a drill tube, of a pump cylinder in connection with the drill tube, a 125 plunger operating in the pump cylinder to create a suction through the drill tube, a cylinder in the pump and tube connection, a plunger in said cylinder movable downwardly in the cylinder under the influence 130

- of the suction, means including a spring for returning said plunger to create an auxiliary suction and keep the fluid flow in the drill tube and connection continuous, and
- 5 means embodied in said plunger in said second cylinder enabling the escape of air and the formation of a water seal on top of the plunger.
6. In a well digging apparatus, an auxiliary cylinder having a funnel at the top for priming, said cylinder being threaded at the base of the funnel, a plunger located in the cylinder, a non-circular plunger rod carried by the plunger, a perforated ring
- 10 threaded into the cylinder and having a non-circular opening to receive and guide the plunger rod, a collar on the plunger rod, a spring between the collar and the ring, and a handle on the plunger rod facilitating the
- 15 unscrewing of the ring and removal of the plunger.
7. In a well digging apparatus, an auxiliary cylinder having a funnel at the top for priming, said cylinder being threaded at the base of the funnel, a plunger located in the cylinder, a non-circular plunger rod carried by the plunger, a perforated ring
- 20 threaded into the cylinder and having a non-circular opening to receive and guide the plunger rod, a collar on the plunger rod, a spring between the collar and the ring, and a handle on the plunger rod facilitating the
- 25 unscrewing of the ring and removal of the plunger, and means including a minute
- 30 opening controlled by a ball valve, for permitting the escape of air from the cylinder and the formation of a water seal on top of the plunger.
8. In a well digging apparatus, a rectangular formation of pipes, a pair of inlet and exhaust flap valves in each side, an exhaust pipe on one end, a suction pipe on the other end, a hose connection to the suction pipe arranged to be connected at the other
- 35 end to a drill tube, pump cylinders between the pairs of flap valves, said cylinders being open at the upper ends, a plunger in each cylinder operating near the open end, means permitting the escape of air through the
- 40 plunger and the formation of a water seal on top, a drain for surplus water, walking beam and crank connections for reciprocating the plungers, the water and gravel columns oscillating in the pump cylinders beneath the plungers, an auxiliary cylinder located in the suction pipe, and an
- 45 automatically operated plunger in the auxiliary cylinder, arranged to move downwardly when the cranks pass between the
- 50 dead centers, said plunger including means comprising a spring for forcing the plunger outwardly when the cranks pass over the

dead centers, to create an auxiliary suction and keep the flow of the stream in the drill tube continuous.

65

9. In a well digging apparatus, the combination with a drill tube located in a well bore, means including a pipe connection joined to the top of the drill tube for creating a swift flowing fluid stream through the drill tube, an exhaust pipe for the fluid and cuttings included in said means, the exhaust fluid returning to the well bore, means enabling the exchanging of the exhaust pipe and pipe connections to force the water through the drill tube and out of the well bore, and means including an automatically operated plunger for insuring the continuity of the fluid flow when the aforesaid pipe connection is connected to the top of the 70 drill tube.

70

10. In a well digging apparatus, a pump cylinder open at the upper end, a plunger operating in the upper portion of the pump cylinder and consisting of a hollow body 75 having a minute opening, a plunger rod pivoted to the plunger, said plunger being removable through the open end of the cylinder for inspection and repair, and a ball controlling the minute opening, enabling the escape of air bubbles from the inside of the cylinder and permitting a small quantity of water to settle on top of the plunger to form a seal.

85

11. In a well digging apparatus, a pair 95 of suction cylinders, a communicating pipe line at the base and forming the mounting for said cylinders, valves in said pipe line at each side of the point of communication of said cylinders therewith, a suction pipe 100 joining the communicating pipe lines and leading to a well tube, and an accessible discharge pipe joining the communicating pipe lines, said discharge pipe enabling the placing of a bucket therebeneath to receive a 105 quantity of the cuttings for examination.

100

12. In a well digging apparatus, a pair 110 of suction cylinders, a communicating pipe line at the base and forming the mounting for said cylinders, valves in said pipe line at each side of the point of communication of said cylinders therewith, a suction pipe 115 joining the communicating pipe lines and leading to a well tube, an accessible discharge pipe joining the communicating pipe lines, said discharge pipe enabling the placing of a bucket therebeneath to receive a 120 quantity of the cuttings for examination, and means including a coupling enabling the joining of said discharge pipe with the suction pipe, to reverse the action of the apparatus.

MILTON N. LATTA.
